UNITED STATES PATENT OFFICE.

WILLIAM B. EWING, OF PEORIA, ILLINOIS.

APPARATUS FOR BURNING LIQUID FUEL.

Application filed September 7, 1923. Serial No. 661,374.

To all whom it may concern:

Be it known that I, WILLIAM B. EWING, a citizen of the United States, and a resident of the city of Peoria, in the county of Peoria and State of Illinois, have invented certain new and useful Improvements in an Apparatus for Burning Liquid Fuel; and I do hereby declare that the following is a full, clear, and exact description of the same, reference being had to the accompanying drawings, and to the numerals of reference marked thereon, which form a part of this specification.

The apparatus disclosed herein is of the general type disclosed in my copending application for U. S. Letters Patent, filed March 2, 1922, Serial No. 540,490.

This invention relates to an improved liquid fuel house heating burner adapted for use in connection with hot air furnaces, boilers and commercial furnaces, and constructed with a minimum of fuel valves and adapted to give a continuous fire, the volume of which is variable at the will of an operator without requiring the operator to know the mechanical nature of the apparatus.

It is an object of this invention to provide a liquid fuel burner constructed to avoid heating of the fuel alone before it reaches the fuel nozzle, thereby eliminating distillation of the fuel.

It is also an object of the invention to provide a liquid fuel burner adapted to use forced draft and low pressure fuel feed thus allowing for exact proportioning of fuel and air under all conditions of weather, resulting in the complete combustion of the fuel and the elimination of waste.

Another object of the invention is the construction of a liquid fuel burner which is practically noiseless and comparatively odorless both as to dripping oil and as to combustion fumes.

It is furthermore an object of this invention to provide an improved liquid fuel household burner of simple and inexpensive construction adapted to be readily installed for use in connection with any furnace and using the method of inducting fuel into an air stream by passing the air stream through a Venturi tube, thereby lowering the pressure below atmosphere, and drawing in fuel which is under atmospheric pressure, or slightly higher.

It is an important object of this invention to provide a liquid fuel burner wherein a cold mixture of air and fuel is directed against the heated walls of a vaporizer housing in such a manner that the larger particles of fuel strike the heated walls and are vaporized before passing into the burner grating.

Other and further important objects of this invention will be apparent from the disclosures in the specification and accompanying drawings.

This invention (in a preferred form) is illustrated in the drawings and hereinafter more fully described.

On the drawings:

Figure 1 is a top plan view of a liquid fuel burner embodying the principles of this invention.

Figure 2 is a side elevation thereof.

Figure 3 is an enlarged vertical detail section taken on line 3-3 of Figure 1.

Figure 4 is an enlarged detail section taken on line 4-4 of Figure 1.

Figure 5 is an enlarged fragmentary detail section taken on line 5-5 of Figure 1.

Figure 6 is a plan view of a modified type of liquid fuel burner for hot air and commercial furnaces where automatic control is not needed, this one being manually controlled.

Figure 7 is a vertical sectional view taken on line 7-7 of Figure 6.

As shown on the drawings:

The dotted line 1 of Figures 1 and 2 indicates the front wall of a furnace having a fire box door. The liquid fuel burner of this invention is adapted for use in connection with a household or commercial furnace and is adapted to be mounted on the exterior at the front of the furnace with the burner grating projecting through the furnace fire box door into the fire box or through the ash pit door.

The improved burner mechanism of this invention comprises a main electric motor 2 connected to drive a main blower 3 which is adapted to blow air into one end of an air duct or pipe 4. A control valve 5 is mounted on the blower 3 and is adjustable by means of a lever or valve stem 6. A Venturi tube 7 is formed in the duct 4. A liquid fuel nozzle 8 has the upper end thereof projecting into the Venturi tube 7 and is controlled by a needle valve 9. The nozzle

- zle 8 is connected to a three-way connector 10, to which one end of a liquid fuel supply pipe or tube 11 is connected leading from a fuel tank 12. Liquid fuel flows by gravity from the tank 12 through the tube 11 into the connector 10 which is provided with a cut-off valve 13. Connected to the tank 12 is a fuel supply pipe 14 and an excess fuel return pipe 15. The return pipe 15 serves to maintain the fuel oil in the tank 12 at a predetermined level represented by the dotted line 16 (Figure 4) the level of which is slightly below the horizontal level of the outlet end of the nozzle 8. An air pressure tube 17 has one end thereof connected to the top of the oil tank 12 for the purpose of giving slightly more than atmospheric pressure on the fuel to give a better spray through the nozzle.
20. The second end of the air duct 4 projects through a casing or housing 18 and is connected to a main or large vaporizer casing 33. A primary or smaller vaporizer casing 19 of cylindrical shape closed at the top 25 and the bottom is mounted within the housing 18 below the vaporizer casing 33. Projecting into the bottom of the primary vaporizer 19 is a pipe stem 20 of a primary grate 21 of annular shape having burner 30 openings 22 therein. The primary grate 21 draws fuel from the vaporizer 19 and when burning serves to heat the primary vaporizer after which the heat passes through the housing 18 into the furnace by way of a 35 large flue or pipe 23. The flue 23 is connected to the top of the housing 18 and projects into the furnace through the fire box or ash pit door. The inner end of the flue 23 is open at 24 (Figure 3).
40. As shown in Figure 3, a preheater is provided within the lower portion of the housing 18 and consists of a grate or gas burner 25 having a gas supply pipe 26 connected therewith. The housing 18 is provided with 45 an opening 27 to permit lighting of the pre-heater burner 25 and the grate 21. Connected to the top of the primary vaporizer 19 is a pipe stem 28 of an annular secondary or auxiliary grate 29 having burner openings 30 in the top thereof adapted to permit fuel from the vaporizer 19 to escape and be ignited. An opening 31 is provided in the housing 18 to permit lighting of the grate 29.
50. Mounted in the housing 18 above the secondary grate 29 is a main vaporizer casing 33 of cylindrical shape. Connected to the top of the main vaporizer casing 33 is a pipe 34 which projects through the flue 23 into the open end thereof where it is attached to an elbow 35. The elbow 35 projects through the flue opening 24 (Figure 3) and has formed on the projecting end thereof a burner casing 36 having seated therein a burner plate or grating 38 having a plurality of burner openings therein. Above
- the burner grate 36, and close to it, is a strike plate 37^a provided with a plurality of concentric slots 37. The object of this plate 37^a is to reduce the velocity of the fuel mixture to a point where it will become ignited and burn without blowing itself out, the flames issuing through the slots 37. A pilot burner 39, fitting tightly in the center of the burner grate 36, serves to ignite the fuel mixture issuing therefrom. The pilot burner 39 is supplied with fuel from the vaporizer 19 through a tube 40.
55. As illustrated in Figure 1, a primary electric motor 41 is provided to drive a primary blower 42 having a valve 43 mounted thereon adapted to be controlled by a lever or valve stem 44. Connected to the primary blower 42 to receive air therefrom is a primary pipe or air duct 45 having a Venturi tube 46 therein. The air duct 45 projects into the housing 18 and is connected to the primary vaporizer 19 to supply the same with fuel. The air pressure tube 17 is connected to the air duct 45 between the blower 42 and the Venturi tube 46.
60. Projecting into the Venturi tube 46 is the upper end of a liquid fuel nozzle 47 controlled by a needle valve operable by the valve stem 48. The nozzle 47 is connected to a three-way connector 49 (Figure 2) having a cut-off valve 50 in the middle arm thereof. The ends of the nozzles 8 and 47 are on the same horizontal level. Connected to the middle arm of the connector 49 is one end of a fuel pipe 51, the other end of which projects into the fuel tank 12.
65. Figures 6 and 7 illustrate a modified form of a liquid fuel burner of a multiple type for use in connection with hot air and commercial furnaces where manual control may be used. This type of burner comprises an electric motor 52 connected to drive a primary blower 53 and a plurality of secondary blowers 54, each of which is provided with a control clutch mechanism 55. Connected to the blower 53 is an air duct 56 having a Venturi tube 57 therein. An air pressure tube 58 is connected to the air duct 56 and to the top of a liquid fuel tank 59. The tank is supplied with fuel oil through a supply pipe 60. An oil return pipe 61 is also connected with the tank 59 to maintain the level of fuel in the tank at a predetermined height slightly below the level of the nozzles. A pipe 62 connects the tank 59 with a valve controlled nozzle 63, the end of which projects into the Venturi tube 57. The nozzle 63 is provided with a shut-off valve 64.
70. Connected to each of the secondary blowers 54 is an air duct 65 having a Venturi tube 66 and also provided with a control valve 67 between the respective blower 54 and the Venturi tube 66. Each Venturi tube 66 is provided with a nozzle similar to the

nozzle 63 and said nozzle is connected with the fuel tank 59 by a pipe 68. Each nozzle is provided with a shut-off valve.

The duct 56 projects into a casing or housing 69 having a flue 70 which is adapted to project into the door of a furnace. The duct 56 is connected to a primary vaporizer casing 71. Projecting into the bottom of the vaporizer casing 71 is a pipe stem of a primary grate 72 having a series of burner openings therein. The primary grate 72 is adapted to draw fuel from the vaporizer 71 and when burning serves to heat the primary vaporizer 71 after which the heat passes through the housing 69 and into the furnace by way of the flue 70.

A preheater is provided in the lower part of the housing 69 and consists of an apertured grate 73 having a gas supply pipe 74 connected therewith.

Connected to the vaporizer 71 is an auxiliary grate 75. A pipe 75 is connected to the grate 75 and projects upwardly in the housing 69 and is closed at its upper end. Connected at intervals in the stand pipe 75 are a plurality of apertured horizontal branch pipes 76, each of which is positioned under a secondary vaporizer casing 77 mounted within the housing 69 one above the other. Each of these pipes 76 has a series of burner openings, each pipe 76 serving as a burner to heat the vaporizer above it. The ducts 65 project into the housing 69 and are connected with the respective vaporizers 77. Attached to the top of each vaporizer 77 is one end of a burner pipe 78. The four pipes 78 project through the flue 70 and into the fire box of the furnace. Each pipe 78 has a burner grate 79 secured thereto. The burner grates 79 are positioned in a horizontal plane within the furnace fire box in parallel relation.

The operation is as follows:

The burner mechanisms are installed on the exterior of the furnace with the burner grate 36 positioned within the fire box of the furnace. To start the device the gas from the gas main 28 is turned on and the preheater grate 25 is lighted with a match or taper through the housing opening 27. After the preheater grate has burned for a short while to heat the primary vaporizer 19 and all the other metal parts, the primary motor 41 is then started and acts to operate the primary blower 42. The valve handle has been adjusted previously to open the air valve 43 so that the blower 42 will force a desired volume of air through the air duct 45 and the Venturi tube 46. Fuel flows by gravity, plus a very low air pressure, from the oil fuel tank 12 through the pipe 51 and into the nozzle tube 47, the cut-off valve 50 of course being opened. Air passing through the duct 45 passes through the Venturi tube 46 at an increased speed thereby

making a pressure depression below atmosphere which condition tends to draw liquid fuel from the end of the nozzle 47. The fuel drawn into the Venturi tube mixes with the passing air, carbureting said air to form a fuel mixture. The fuel mixture passes into the primary vaporizer 19 where it is vaporized due to the heated condition of the vaporizer. The vaporized fuel mixture from the vaporizer 19 flows into the primary burner grate 21 and leaving through the apertures 22 is ignited by the gas flames from the pre-heater 25. The fuel mixture from the vaporizer 19 also flows into the grate 29 and out through the apertures 30 and through the pipe 40 out of the pilot burner 39. The grate 29 is lighted with a taper or torch through the housing opening 31. The pilot burner is lighted by a taper or torch through the middle opening in the strike plate 37.

The preheater 25 is now turned off leaving the grate 21 burning. The auxiliary grate 29 is provided to give sufficient heat on the bottom of the main vaporizer 33 to vaporize any liquid collected therein. The main vaporizer 33 is thus heated and the main motor 2 is started. The main blower 3 is thus operated to force air through the air duct 4 and then through the Venturi tube 7 at an increased speed to draw liquid fuel from the nozzle 8. The mixture of air and fuel thus passes into the heated main vaporizer 33 and is vaporized and passes upwardly through the flue 34 and out through the burner grate plate 38 at a velocity greater than the rate of flame propagation. The fuel mixture escaping from the burner plate 38 is ignited by the flame from the pilot 39. The flames from the burner grate 38 act as the main source of heat for the furnace and house.

To shut off the main burner 38, the shut-off valve 13 is first closed and then after a short time, about one-half of a minute, the main blower 3 and the main motor 2 are stopped. This procedure is very important since it eliminates all back fire. By this method the fuel mixture becomes so thin that it will not burn, by the time the velocity through the burner holes becomes slower than the rate of flame propagation. The main burner is stopped and starts automatically by a thermostatic control not shown in drawings. On cold nights, the grates 21 and 29 may be left burning all night. On mild nights, the grates 21 and 29 may be turned off by closing the cut-off valve 50, and a moment later shutting off the motor 41. When this is done, the preheater must be used to again start the device.

The housing 18 which encloses the vaporizers 19 and 33 acts as a jacket and serves to retain the heat around the vaporizers to properly heat the same to cause rapid va-

porization of the fuel mixture entering the vaporizers from the air ducts and Venturi tubes, and to preheat the metallic parts to prevent condensation of vapor on cold metal. The flue 23 serves the double purpose of carrying the heat from the grates 21, 25 and 29 to the furnace and preheating the metallic parts 34, 35, 36 and 38 so that the fuel vapor will not condense on a cold surface.

It will be noted that a cold mixture of air and fuel is delivered into the vaporizers and is directed tangentially against the inner peripheral walls of the vaporizers in such a manner that the larger particles of fuel strike the heated walls of the vaporizers and are rapidly vaporized before passing from the vaporizers into the respective grates or burners.

10 The air pressure pipe 17 connecting the fuel tank with the air duct 45 serves to increase the air pressure in the tank 12 above atmospheric pressure with the result that the fuel from the tank will flow through the nozzles with greater force to be mixed with the air passing through the Venturi tubes.

15 The operation of the multiple type of burner mechanism illustrated in Figures 6 and 7 is similar to that already described. In this case, however, a plurality of secondary blowers 54 are provided operable through individual control clutches 55 from the motor 52. Each air duct 65 is equipped with a separate control valve 67 and a separate nozzle so that the supply of fuel mixture to the separate secondary vaporizers may be independently controlled. The auxiliary grates 76 are so positioned that one will cause lighting of the other.

20 It will be noted that this invention provides a method of heating houses and the like by using in connection with a furnace a liquid fuel burner mechanism which is adapted to be installed on the exterior of the furnace with the exception of the burner grates which are positioned in the fire box of the furnace. The method referred to briefly consists in preheating an enclosed vaporizer into which a cold fuel mixture of air and oil is directed with force after passing through a Venturi tube or carburetor through which air is forced by a blower and into which oil from a low pressure oil tank is drawn either at atmospheric pressure or slightly higher. The fuel mixture is directed into the heated vaporizer and is vaporized, passing into burner grates which are ignited by the preheater or by hand and serves to continue to heat the vaporizer and 25 also act to heat one or more secondary vaporizers, each of which has a furnace burner grate connected therewith and is independently supplied with a cold mixture of air and oil which is to be heated and vaporized to form a fuel mixture for use in the

furnace burner grates to cause the furnace to produce the necessary heat to heat the house in which it is installed.

Attention is called to the fact that the burner may be easily installed in an old furnace without the necessity of cutting out part of the furnace walls and without the use of refractory material.

20 I am aware that numerous details of construction may be varied through a wide range without departing from the principles of this invention, and I therefore do not purpose limiting the patent granted otherwise than necessitated by the prior art.

25 I claim as my invention:

1. A liquid fuel burner comprising a motor, a blower connected to be driven thereby, a valve controlling the entrance of air into said blower, an air duct connected with the blower, a liquid fuel tank, a Venturi tube formed in said air duct, a valve controlled nozzle projecting into said Venturi tube, a pipe connecting said nozzle with said tank with a cut-off valve inserted in said pipe, an air pressure pipe connecting said tank with 30 said air duct, a housing, a flue formed thereon, a primary vaporizer casing in said housing to which the air duct is connected, a preheater in said housing for initially heating the primary vaporizer, a plurality of 35 burner grates connected with said primary vaporizer to receive a fuel mixture therefrom, a secondary vaporizer casing in said housing adapted to be heated by one of said burner grates, means connected with said secondary vaporizer casing to supply a fuel mixture thereto to be vaporized, a pipe connected to said secondary vaporizer and projecting through said flue, a burner grate connected to the end of said pipe, a pilot 40 burner in said last mentioned burner grate, and a tube connecting said pilot burner with the primary vaporizer casing.

45 2. A liquid fuel burner device comprising a housing having a flue, primary and secondary vaporizer casings in said housing, a main burner grate connected with the secondary vaporizer casing, a plurality of auxiliary burner grates connected with the primary vaporizer casing for heating said vaporizer casings, a preheater in said housing for initially heating the primary vaporizer casing, air ducts connected with said vaporizer casing, Venturi tubes formed in said air ducts, liquid fuel nozzles projecting into 50 said Venturi tubes, means for supplying a liquid fuel to said nozzles, and mechanism connected with said air ducts for forcing air through said air ducts and Venturi tubes to cause the air to be carbureted with the liquid fuel from the nozzles to form a fuel mixture adapted to be projected into said vaporizer casings and vaporized.

55 3. A liquid fuel burner device comprising a housing, primary and main vaporizer

- casings in said housing, a main burner grate connected with said main vaporizer casing, a plurality of auxiliary burner grates in said housing connected to said primary vaporizer casing to heat said vaporizer casings, a preheater in said housing for initially heating the primary vaporizer casing, and mechanisms connected with said vaporizer casings adapted to supply the same with a fuel mixture to be vaporized to provide a vaporized fuel mixture for use in the auxiliary burner grates and in said main burner grate.
4. A liquid fuel burner device comprising a housing, vaporizers in said housing, burner grates in said housing connected with said vaporizers, a preheater in said housing for initially heating the vaporizers, air ducts projecting into the housing and connected with said vaporizers, Venturi tubes formed in said air ducts, means connected with the air ducts to force air therethrough and through the Venturi tubes, and means for feeding a liquid fuel into said Venturi tubes to carburete the air passing therethrough to form a fuel mixture adapted to be vaporized in said vaporizers to form a vaporized fuel mixture adapted for use in said burner grates.
5. A liquid fuel burner device comprising a housing, vaporizers therein, burner grates connected with said vaporizers, a preheater in said housing for initially heating said vaporizers, air ducts connected with said vaporizers, restricted tubes forming a part of said air ducts, valve controlled means connected with the air ducts to force air therethrough and through said restricted tubes, liquid fuel nozzles projecting into said restricted tubes, valves in said nozzles, and means connected with said nozzles for supplying liquid fuel thereto.
6. In a liquid fuel burner device, the combination with a housing, of a plurality of vaporizers therein, a preheater in said housing for initially heating one of said vaporizers, a burner grate connected to said va-
- porizer adapted to be lighted by the preheater, burner means connected to said vaporizer also adapted to be lighted by hand to cause heating of the remaining vaporizers, and mechanisms for supplying a cold mixture of air and liquid fuel to the vaporizers to be vaporized therein to form a heated vaporized fuel mixture.
7. In a liquid fuel burner device, the combination with a housing, of primary and main vaporizers therein, a preheater in said housing for initially heating the primary vaporizer, burner grates connected with the primary vaporizer, main burner grates connected with said main vaporizers, restricted air ducts connected with said primary and main vaporizers, means for feeding a liquid fuel into said restricted air ducts, and means for forcing air through the restricted air ducts to be carbureted with the liquid fuel and then pass into the primary and secondary vaporizers to be heated and vaporized to form a heated vaporized fuel mixture for use in the burner grates connected with the vaporizers.
8. A liquid fuel burner device comprising a plurality of vaporizers, burner grates therefor, constricted air ducts connected with said vaporizers, liquid fuel nozzles projecting into said air ducts, fuel pressure means connected with said nozzles to supply liquid fuel thereto, valve controlled blowers connected with said air ducts, and means for operating the blowers to cause the same to force air through the air ducts to be carbureted with the liquid fuel and then pass into the vaporizers to be vaporized to afford a fuel mixture for use in the burner grates.

In testimony whereof I have hereunto subscribed my name in the presence of two subscribing witnesses:

WILLIAM B. EWING.
